UNITED STATES PATENT OFFICE.

VICTOR ALEXA, OF CHICAGO, ILLINOIS.

UNIVERSAL DRAFTING-MACHINE.

1,311,867.

Specification of Letters Patent.

Patented Aug. 5, 1919.

Application filed July 27, 1916. Serial No. 111,617.

To all whom it may concern:

Be it known that I, VICTOR ALEXA, a citizen of the United States of America, and a resident of Chicago, county of Cook, and 5 State of Illinois, have invented certain new and useful Improvements in Universal Drafting Machines, of which the following is a specification.

This invention relates to improvements in 10 drawing tables of the rotatable type, which are provided with a relatively adjustable straight edge and which combine in one device means for accomplishing the results usually attained by the use of a T-square, 15 triangles, bevel protractors, centrilineads, section liners, cylindrical shading instruments, and rules or scales.

An object of the invention is to provide 20 an improved drawing table which may be easily and instantly adjusted in height, and to any desired angle, in order that the draftsman may work in a standing position or upright sitting position.

Further objects of the invention are to 25 provide an improved construction of circular graduated disk for supporting the material for receiving the drawing; to provide improved means for locking the disk in any desired angular position, to enable the 30 drawing of all straight lines of whatever angle from left to right along an adjustable ruling blade; to provide an improved construction for adjusting the ruling blade; to provide in connection with said ruling 35 blade an improved section lining device and an improved means for effecting graduated shading; to provide improvements in the ruling blade and adjusting mechanism whereby this mechanism may be 40 thrown into or out of operative relationship with the ruling blade and the latter adjusted by the hand, as desired; and to provide improved means for attaching scales to the ruling device and drawing board to 45 enable the draftsman to quickly change from the English measure to the metric or other measure, as desired.

An illustrative embodiment of this invention is shown in the accompanying drawings, in which:

Figure 1 shows in side elevation a drawing table constructed according to this invention.

Fig. 2 represents a front elevation of the 55 device.

Fig. 3 is a detail in plan of the rotatable paper supporting disk and shows the relationship between this disk and the adjustable ruling blade.

Fig. 4 is a side view of the mechanism 60 shown in Fig. 3.

Fig. 5 shows a lower end elevation of the mechanism shown in Fig. 3.

Fig. 6 is an enlarged fragmentary plan view of the rotatable paper supporting disk 65 and shows the means for clamping paper thereon.

Fig. 7 shows in elevation a detail of the paper clamping device.

Fig. 8 is an end view of the paper clamp- 70 ing device.

Fig. 9 is an enlarged plan view of the adjusting device for the ruling blade.

Fig. 10 is a sectional view taken on the line B—B of Fig. 9. 75

Fig. 11 is a sectional detail taken on the line A—A of Fig. 9.

Drawing tables of the general type where- 80 in the use of angles, protractors, etc., is dis- 85 pensed with, have usually been provided with more or less complicated and unnecessary constructions. The purposes of the present invention are to provide an improved and simplified construction with which all of the work which could be ac- 85 complished by the use of prior rotary drawing boards may be attained, and in addition further results may be attained, such as producing sectional and graduated shading, quick adjustment of the ruling blade 90 and operation of the means for stretching and clamping the drawing material to the rotatable board.

Referring to the drawings, the drawing 95 table comprises a frame 1 to which is pivot- ally attached by means of arms 2 a rectangular frame 3 for supporting the rotatable board 4. The arms 2 and frame 3 may be adjusted around their pivotal supports 5 and locked in any desired angular position 100 by means of a dog 6 which is suitably formed to engage any one of a series of seats or notches 7 in the frame 1. The frame 3 may also be adjusted angularly around its pivotal connections 8 with arms 2, to suit 105 the convenience of the draftsman while drawing, or to permit the frame 3 to assume an inverted horizontal position when the table is not in use.

The frame 1 is preferably provided with 110

a horizontal ledge 9 for supporting tool-holders 10 and 11 and an adjustable copy support 12.

The frame member or table 3 is provided 5 with a centrally located bearing 13 for a stub shaft 14 which is rigidly secured to the rotatable drawing board 4. The rotatable board 4 is of circular disk shape and preferably marked with degree graduations 15 10 around its periphery, as shown in Fig. 3. The disk 4 has rigidly secured thereto a rectangular drawing board 16 which is located between the four arms 17 also secured to the disk 4. The members 17 may support 15 removable scales 18 and 19 as shown in Fig. 3, and a space is provided between the members 17 and drawing board 16 for paper clamping yokes 20. The yokes 20 are pivotally secured to the drawing board 16 by 20 means of headed studs 21 which are riveted to the yokes, as shown in Fig. 6, and extend through L-shaped slots 22 in metal plates 23 secured to the two sides of the board 16. The heads 24 of studs 21 extend into recesses 25 25 in the sides of the drawing board 16 and are engaged by the ends 26 of springs 27. These springs are secured to the board 16 by means of the screws 28, and the function of the springs is to urge the clamping yokes 20 30 to the right, Fig. 7, along the L-shaped slots 22, so that the parts 29 of the yokes will firmly clamp the edges of the drawing material 30 of any desired thickness against the ends of the board 16. Clamping yokes 35 20 may be provided with operating handles 31 as shown in Fig. 3. The board 16 is preferably beveled at the edges 32 thereof, located adjacent to the parts 29 of yokes 20, in order that when paper is placed on the board 40 16 and the yoke members rock downwardly into clamping position, the paper will be stretched tight over the board.

For the purpose of providing a suitable support along which a ruling blade 33 is 45 adjustable, the frame or table member 3 has secured thereto at its left edge an angle bar 34, as shown in Figs. 5 and 11. The angle bar 34 at its ends is provided with bracket members 35 within which is mounted a rod 50 36 of circular cross section, and slidable on rod 36 is a supporting plate 37 for the ruling blade 33. The plate 37 has downwardly extending apertured ears 39 forming bearings on the rod 36. The ruling blade 33 is 55 secured to plate 37 by means of the screws 40 as shown in Fig. 9, and to one side of the ruling blade and pivotally mounted on plate 37 is a bearing member 41 which serves to support the device for positively adjusting 60 the ruling blade along rod 36. The bearing member 41 is pivoted to plate 37 by means of the screw 42 which is tapped into plate 37. The plate 41 is provided with sleeves 43 and 44 extending upwardly and downwardly 65 therefrom and providing the bearing for the

spindle 45 rotatably mounted thereon. Screwed to the lower end of spindle 45 is a pinion 46 in position to mesh with a rack 67 fast to the angle bar 34. With this construction, rotation of spindle 45 will cause 70 the pinion 46 to roll along the fixed rack 67 and thereby shift the bearing member 41 and parts mounted thereon. The spindle 45 may be thus rotated by means of a toothed disk 47, which is preferably pinned to spindle 45 75 by the pin 48, as shown in Fig. 11.

For the purpose of differentially rotating the toothed disk 47 definite predetermined extents, a lever 49 is journaled on the sleeve 43 and carries a spring-pressed double pawl 80 50 for engagement with the toothed disk 47. This pawl may be rocked from one side to the other of its central position as shown in Fig. 9, so that it will engage and drive disk 47 on the up or down strokes of the operating handle 49. The motion of lever 49 may be limited in either direction by means of adjustable stops 51 and 52 in the form of upstanding lugs on disks 53 and 54, which are rotatably mounted on sleeve 43. The stops 51 and 52 coöperate with a lug 55 integral with the operating handle 49. The disks 53 and 54 may be locked in any desired angular position by means of a clamp arm 56 which has threaded engagement with a screw 57 tapped into and extending upwardly from a disk 58 secured to the bearing member 41. Thus by rocking clamping arm 56 to the right, Fig. 9, each of disks 53 and 54 is released and may then be rotated to 100 shift the stops 51 and 52 to the desired position with respect to lug 55 on the operating lever. The disks 53 and 54 have circular slots 59 at the location of screw 58. When the stops 51 and 52 are adjusted as desired, 105 the same are locked into position by rocking the clamping arm to the left, thereby causing it to clamp the disks 53 and 54 against the fixed plate or disk 58. The bearing plate 41 is rotatable around its pivot 42, for the 110 purpose of engaging and disengaging the pinion 46 from the rack 67. The plate 41 may be locked in either of its set positions by means of a locking clamp 60, which has threaded engagement with a screw 61 extending upwardly from the plate 37.

The pawl 50 is preferably made wider than the toothed wheel 47, in order that this pawl may engage different removable toothed wheels 62 which may be placed over the hub of the wheel 47 and secured thereto by a dowel-pin 63 extending upwardly from wheel 47 into apertures in the toothed members 62. The members 62 may be formed, for example as shown in Fig. 9, 115 with notches 64 in the periphery of each spaced different distances apart. The arrangement shown is suitable for shading curved surfaces, such as a shaft. Thus, the first operation of lever 49 may shift the 120 125 130

ruling blade only a very slight extent, whereas on succeeding operations of the lever, the ruling blade is shifted successively increasing extents.

- 5 For the purpose of supporting a scale 68 along the path of travel of the ruling blade 33, an angle bar 69 is secured to the bracket members 35 and supports a guideway 70 for the ruling blade. A bar 71 rigid with 10 the angle bar 69 extends along the inner edge 72 of the supporting plate 37 and assists the rod 36 in guiding and preventing displacement of plate 37 when it is shifted along the rod 36.
- 15 The ruling blade is preferably cut away at 75 at its ruling edge in line with the figures on scale 68, to permit of easily reading the position of the ruling blade. The blade is also beveled to a comparatively 20 sharp edge 76 adjacent to the graduations on the scale, for the purpose of minimizing any likelihood of error in adjusting the same.

In the operation of the device, the ruling 25 blade 33 may be quickly adjusted to any desired position along the rod 36 by simply rocking the blade upwardly around said rod, thereby disengaging pinion 46 from rack 67 and then shifting the blade along 30 the rod, or the bearing rod 41 may be adjusted to a position where the pinion is unmeshed from the rack, thus permitting the ruling blade to slide freely along the guide rod while remaining in contact with the 35 drawing board. The blade may be very accurately adjusted by rotating the toothed disk 47 causing pinion 46 to roll along rack 67 and shift the supporting plate 37 and mechanism mounted thereon. The disk 47 40 may be rotated directly by the hand or through the lever 49. If it is desired to shift the ruling blade definite distances such as are required in sectional lining, the stops 51 and 52 are adjusted to regulate the 45 throw of the operating lever 49.

Should it be desired to successively shift the ruling blade definite variable extents, the desired one of notched disks 62 is placed over the hub of the toothed wheel 47. The 50 disks 62 are preferably of somewhat greater diameter than the wheel 47 and thereby serve to disengage pawl 50 from said wheel. Upon the operation of the operating handle 49, the spindle 45 and pinion thereon are 55 rotated different extents according to the spacing of notches 64 in disk 62.

The circular board 4 may be rotated and clamped in any desired angular position, and accordingly, the usual triangles and protractors may be dispensed with, all lines of 60 whatever angle being drawn from left to right along the ruling blade 33.

Although but one specific embodiment of 65 this invention has been herein shown and described, it will be understood that numer-

ous details of the construction shown may be altered or omitted without departing from the spirit of this invention as defined by the following claims.

I claim:

1. A device of the class described, comprising a supporting frame, a drawing board mounted thereon to rotate in its own plane, a ruling blade mounted for adjustment transversely of the axis of said drawing board, means for adjusting said ruling blade, comprising a fixed rack, a rotatable pinion carried by said ruling blade in position to engage said rack, means for rotating said pinion, and means for guiding said 70 ruling blade as driven by said pinion.

2. A device of the class described, comprising a supporting structure, a drawing board mounted thereon to rotate in its own plane, a guide rod secured to said supporting structure, a ruling blade slidably mounted on said guide rod, a pinion journaled on said ruling blade, a rack secured to said supporting structure in position to be engaged by said pinion, and means for rotating said pinion for the purpose of shifting 85 said ruling blade along said guide rod.

3. A device of the class described, comprising a supporting structure, a drawing board mounted thereon for rotation in its own plane, a guide rod secured to said supporting frame at right angles to the axis of said drawing board, a ruling blade pivotally and slidably mounted on said guide rod, a pinion carried by said ruling blade, and 90 a rack fixed to said supporting frame in position to be engaged by said pinion.

4. A device of the class described, comprising a supporting frame, a drawing board mounted thereon to rotate in its own plane, a ruling blade, fixed guides for said ruling blade whereby the same may be shifted transversely of the axis of said drawing board, and adjustable means mounted on said ruling blade for causing 105 said ruling blade to travel along said guiding means.

5. A device of the class described, comprising a supporting frame, a drawing board mounted thereon to rotate in its own plane, a ruling blade mounted on said frame for adjustment transversely to the axis of said drawing board, means for adjusting said ruling blade, comprising a pinion rotatably mounted on said ruling blade, a rack 115 fixed to said supporting frame in position to mesh with said pinion, a toothed wheel rigid with said pinion, and an arm pivoted concentric with said toothed wheel and provided with a pawl for engaging and rotating 120 said wheel upon oscillation of said arm.

6. A device of the class described, comprising a supporting frame, a drawing board mounted thereon to rotate in its own plane, a ruling blade mounted on said frame 125

for adjustment transversely to the axis of said drawing board, means for adjusting said ruling blade, comprising a pinion rotatably mounted on said ruling blade, a 5 rack fixed to said supporting frame in position to mesh with said pinion, a toothed wheel rigid with said pinion, an arm pivoted concentric with said toothed wheel and provided with a pawl for engaging and 10 rotating said wheel upon oscillation of said arm, and adjustable means on said ruling blade for limiting the motion of said arm.

7. In a device of the class described, the combination with a drawing board, of a 15 guide secured thereto, a ruling blade slidably mounted on said guide, a rack extending along the path of movement of said ruling blade, a pinion carried by said ruling blade, and means for moving said pinion 20 into and out of mesh with said rack.

8. A device of the class described, comprising a supporting frame, a drawing board mounted thereon to rotate in its own

plane, a ruling blade, fixed guides for said 25 ruling blade whereby the same may be shifted transversely of the axis of said drawing board, and adjustable means mounted on said ruling blade for causing said ruling blade to travel step by step along said guiding means.

9. In a device of the class described, the combination with a drawing board, of a 30 guide secured thereto, a ruling blade slidably mounted on said guide, means mounted on said blade for shifting the blade along said guide, said means including a pivoted operating lever, a pair of adjustable shouldered stops pivoted concentric with said operating lever and for limiting the motion of said lever in either direction, and 35 means for clamping said stops in different angular positions with respect to said operating lever.

Signed at Chicago this 25th day of July, 1916.

VICTOR ALEXA.
